DESIGN.

J. L. FOLSOM.

CARPET.

No. 18,229.

Patented Apr. 3, 1888.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 18,229, dated April 3, 1888.

Application filed January 26, 1888. Serial No. 262,049. Term of patent 3½ years.

To all whom it may concern:

Be it known that I, JAMES L. FOLSOM, of Brooklyn, in the county of Kings and State of New York, have invented a new and original 5 Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view 15 of a carpet showing my new design.

The characteristic feature of my design is the triple figure A, which is repeated in successive rows over the face of the carpet. The figure A is composed of the three parallel

bars of a coral-like character, having projections and depressions partly corresponding with one another, whereby the outlines of adjacent bars in general follow each other. These triple figures are alternately reversed in position, so that the bars of one figure extend in a direction different from that of the bars in the adjoining figure. The spaces between these figures contain here and there small forms like pieces of coral broken from the larger branches. The whole is arranged upon a suitable ground. 20 25 30

What I claim as new, and desire to secure by Letters Patent, is—

The design for carpets, consisting of the design substantially as shown.

JAS. L. FOLSOM.
